UNITED STATES PATENT OFFICE.

MACK T. TAYLOR, OF FORT WORTH, TEXAS.

GARBAGE-CAN.

No. 926,684.

Specification of Letters Patent.

Patented June 29, 1909.

Application filed October 24, 1908. Serial No. 459,311.

To all whom it may concern:

Be it known that I, MACK T. TAYLOR, a citizen of the United States, residing at Fort Worth, Texas, have invented certain new and useful Improvements in Garbage-Cans, of which the following is a specification.

This invention relates to receptacles for receiving trash or other matter and particularly to receptacles for placing on side walks and other conspicuous places to receive trash which might be otherwise thrown on the streets and other places, and the object is to provide such receptacles with certain attachments which will automatically close the receptacles when the trash falls into the receptacles so that the trash is covered from view and so that bad odors will not rise up from the trash.

Another object is to provide such receptacles with inner removable cans which will receive the trash and which can be removed to dump the trash into garbage wagons without having to move the outer inclosing walls. With such arrangement the outer walls remain smooth and do not become unsightly and battered from rough usage.

Another advantage is that the outer inclosing walls are made removable so that they can be removed whenever desirable and new walls put in their places. This arrangement is useful for advertising purposes. New advertising matter may be used as often as desirable and the receptacles do not have to be carried to the painter's shop when the advertising matter is to be changed.

Other objects and advantages will be fully explained in the following description and the invention will be more particularly pointed out in the claim.

Reference is had to the accompanying drawings which form a part of this application and specification.

Figure 1 is a side elevation of a garbage receptacle constructed in accordance with this invention. Fig. 2 is a top plan view of the receptacle on a larger scale than Fig. 1 and showing the device without the top. Fig. 3 is a horizontal section on a smaller scale than Fig. 2. Fig. 4 is an inverted plan view of the top or cover. Fig. 5 is a vertical section of the receptacle on a larger scale than previous views. Fig. 6 is a broken sectional view, illustrating the manner of attaching the removable portions of the cover.

Fig. 7 is a broken plan view, showing the construction of the parts shown in Fig. 6.

Similar characters of reference are used to indicate the same parts throughout the several views:

This invention includes an outer inclosure which is provided, with a removable top which has automatic closing devices and includes an inner removable receptacle, the outer inclosure being provided with a door which is co-extensive with the dimensions of the side of the inclosure. The outer inclosure is provided with a top rim 1 which may be a single casting. Angle irons 3 constitute the frame at three sides of the bottom and at two corners of the upright walls of the outer inclosure. At the bottom adjacent to the door a bar 4 is attached to the bottom angle irons 3. Adjacent to the door the upright frame pieces consist of flat bars 5. Pockets are formed on the upright bars 3 and 5 by attaching strips 7 thereto and bending the same twice to receive the inclosing side pieces 6. At the bottom, the side walls 6 rest inside of the upright flange 80 of the angle bars 3. The side walls 6 are thus loosely mounted in the pockets formed to receive them and are easily removable.

The side walls are useful for advertising purposes and may be removed as often as desirable and other side walls put in their places. This construction is also desirable because a battered or broken side wall can be replaced with a new side wall.

The door 8 constitutes one of the side walls. The door is formed of flat bars 8' for a frame and pockets 7 attached thereto to receive wall portion 8. The door is hinged to the outer receptacle by hinges 9 and a locking device is provided which consists of sockets 95 attached to the wall of the outer receptacle and a socket 10' attached to the door. A key 10" is inserted in the sockets when they are brought into alignment with each other.

An inner garbage holder 11 is placed loosely within the outer receptacle and may be removed through the side door 8 as often as it is necessary to discharge the accumulations therein. The garbage receptacle 11 rests on the frame pieces 4 and 12 and on the angle irons or bars 3.

The top of the device is removable, being loosely mounted on the outer inclosure by means of the flanges 2 which rest on the cast-

ing 1. The top is also provided with strips 2' attached to the under side thereof to form a flange to project down with the frame piece 1 so that the top will be held against displacement. The top is provided with automatically closing doors 15. The doors 15 have flanges 17 which are bent over bars 18 which are pivotally mounted in the staples or loops 19. Weights 16 are suspended on the flanges 17 and thus hold the doors 15 normally closed, but are yielding so that the doors may be pressed open to receive trash. Attention is called to the construction of the bars 18 which have thin edges at the bottom so that there will be little friction during operation. The top has substantially angular flanges 20 which project downwardly to aid in guiding the trash into the receptacle 11. The top has braces consisting of T-bars 21. The four pieces 22 constituting the sloping sides of the top are made removable and are secured to the T-bars 21 by bolts 23 which are provided with nuts 24, the nuts 24 being soldered to the undersides 25 of the T-bars 21.

Having fully described my invention, what I claim as new and desire to secure by Letters Patent, is,—

In a garbage receptacle, an outer inclosure, a door hinged thereto, a removable can with- 30 in said inclosure, a cover engaging said outer inclosure, a hopper formed in said cover, bars pivotally attached to the lower edges of said hopper, doors consisting of bent plates mounted on said bars and having the longer portions thereof projecting normally under said hopper and forming the bottom thereof, weights suspended on the other portions of said plates and holding the doors yieldingly 35 closed, and guides attached to the lower edges of said hopper and coöperating with said doors to guide trash to said removable can. 40

In testimony whereof, I set my hand in the presence of two witnesses, this 5th day of October, 1908.

MACK T. TAYLOR.
